(57) **CLAIM**

The ornamental design for manifold type electro-magnetic valve, as shown and described.

DESCRIPTION

FIG. 1 is a top and left front perspective view of manifold type electro-magnetic valve showing our new design;

FIG. 2 is a top and right rear perspective view thereof;

FIG. 3 is a top plan view thereof;

FIG. 4 is a front elevational view thereof;

FIG. 5 is a rear elevational view thereof;

FIG. 6 is a right side elevational view thereof; and,

FIG. 7 is a left side elevational view thereof.

The phantom line showing in the drawings is for illustrative purposes only and forms no part of the claimed design.

The portion of the left side of the article not shown in the drawing or described in the specification forms no part of the claimed design.
